UNITED STATES PATENT OFFICE.

FLOYD O. GRAPP, OF MINNEAPOLIS, MINNESOTA.

WASTE CHUTE.

Application filed January 26, 1927. Serial No. 163,697.

This invention relates to waste chutes, for use particularly in the kitchens of homes where dirt, paper and other rubbish are apt to accumulate, and the primary object is to provide a comparatively simple, easily operated and practical device for such purposes. A further object is to provide, in connection with the chute proper, a trap door and a frame therefor, which are constructed in a particularly novel manner. A further object is to provide means, of an extremely simple and economical construction, for imparting a yielding resistance to the material in the chute, whereby an accumulation of such material will prevent an updraft through the chute. Still further and more specific objects will be disclosed in the course of the following specification, reference being had to the accompanying drawing, wherein:

Fig. 1 is a perspective view of the device, as installed, various parts being broken away for purpose of illustration.

Fig. 2 is a perspective view of the upper portion of the device, showing the trap door in an open position.

Fig. 3 is an enlarged top or plan view of the device, a portion of the cover being broken out.

Fig. 4 is a detail section, as on the line 4—4 in Fig. 3.

Referring to the drawing more particularly and by reference characters A designates the floor, of a kitchen or other room or hall, in which the device is to be installed, it being understood that such room is directly over a basement into which the chute will extend, and in which basement there will be placed a suitable receptacle to receive the waste material from the chute.

The device consists primarily of four parts, the chute B, a retainer C, a frame D, and a door E.

The frame D has four rectangularly arranged, vertical flanges 5, 6, 7, and 8, the first three of which are provided with marginal horizontal flanges 9, 10 and 11, the top faces of which are higher than the top edge of the flange 8, but whose outer edges are rounded off so as to form a smoother joint with the floor A. The vertical flanges 5 and 7 are provided with a pair of opposite, inwardly disposed studs 12. The parts 5 to 12, inclusive, are preferably all cast into one integral piece, thus greatly simplifying and cheapening the cost of production. The

door E is a flat cast plate, having a pair of end flanges 13 which continue in notched ears 13^a for bearing engagement with the studs 12. It will be noted that no rivets, 60 screws or bolts are required to secure the door. It is merely laid in place while held horizontally, and may similarly be lifted off, but cannot be removed from the studs 12, when tilted, because it would first stop 65 against the rear part of the frame. It will also be noted that the door need not be provided with any handles or grips, for opening it, and that it is perfectly flush with the frame D, thereby giving it a finished effect 70 and eliminating any projections for catching dirt or being stumbled over. Furthermore, the housewife, or other operator, does not need to stoop down to open the door with her hands. The door is so constructed and 75 arranged that by slightly depressing its rear edge portion (see dotted lines in Fig. 4) with one foot, the toe or sole of the other foot may be engaged under the front edge, after which the door can be tripped to the 80 open position, as shown in Fig. 2. A slight counter or reverse movement will cause the door to drop back into its initial position. It may here be noted that, as the flange 8 has no horizontal or upper flange, when the 85 door is lifted up there is nothing at the front end of the frame, to project above the floor level and thus hinder dirt from being swept into the chute, and still it is unnecessary to groove out or rabbet the floor, 90 about the main hole, to receive any part of the frame. Of course, if the floor is laid with linoleum or similar covering, it would no doubt be advisable, at least in some instances, to provide such covering with a 95 larger rectangular opening to receive flanges 9, 10, 11, and thereby leave the top of the door and frame substantially flush with the floor covering.

The chute B, proper, is rectangular in 100 cross section, is preferably made of sheet metal, and is secured, at its upper end, to the flanges 5—6—7—8, by any suitable means such as rivets 14. The length of the chute is determined by the depth of the basement, 105 the height of the receiving receptacle, and the desires of the purchaser.

In chutes of this character, one of the difficulties sometimes experienced is that when the door is opened there is an updraft 110 of air which is occasionally strong enough to carry a certain amount of dust back into

the room. Spring held baffles or yielding doors, lower in the chute, will overcome this difficulty, but such devices are apt to become out of order, and obviously add considerable 5 to the cost of manufacture, and would increase the sales cost, with a corresponding decrease in the number of sales to householders of moderate means.

To provide simple and economical means 10 for preventing updraft, I have devised the member C, which consists of a pair of integrally or continuously formed spring acting tines or prongs 15, the joined ends of which are rigidly secured upon the inside 15 of the chute B, as by a bolt or rivet 16. These prongs extend angularly across the passage of the chute, as shown in Figs. 1 and 3, and by so doing affect a yieldable 20 obstruction for the paper and other rubbish thrown or swept into the chute. Thus, the column of rubbish above the prongs will obstruct the updraft, and when the upper part of the chute is well filled, it is a simple matter to push the column down, as far as 25 necessary, to leave space for additional rubbish, it being understood that the prongs 15 will yield sufficiently to permit such lowering of the rubbish column.

It is understood that suitable modifications 30 may be made in the general design and structural details of the invention as herein shown and described provided, however, that said modifications come within the spirit and scope of the appended claims. 35 Having now therefore fully shown and described my invention, what I claim to be new and desire to protect by Letters Patent is:

1. In a device of the character described, 40 a rectangular frame adapted to be arranged in a floor opening and having horizontal flanges at its sides and rear for resting on the floor about three sides of the opening, the fourth side of the frame being not higher than the floor surface, a cover pivotally 45 carried in the frame, near the rear thereof, and adapted, when closed, to extend over said fourth side of the frame, and a chute extending downwardly from the frame.

2. In a device of the character described, 50 a rectangular frame adapted to be arranged in a floor opening and having horizontal flanges at its sides and rear for resting on the floor about three sides of the opening, the fourth side of the frame being not higher than the floor surface, a cover pivotally 55

carried in the frame, near the rear thereof, and adapted, when closed, to extend over said fourth side of the frame, and a chute extending downwardly from the frame, 60 said cover being inset in the frame so as to be flush with said horizontal flanges.

3. In a device of the character described, 65 a rectangular frame adapted to be arranged in a floor opening and having horizontal flanges at its sides and rear for resting on the floor about three sides of the opening, the fourth side of the frame being not higher than the floor surface, a cover pivotally 70 carried in the frame, near the rear thereof, and adapted, when closed to extend over said fourth side of the frame, and a chute extending downwardly from the frame, said cover being so mounted that pressure upon its rear end will cause the front edge to raise, 75 whereby the operator may open the cover with her feet and without stooping.

4. A waste chute comprising a rectangular 80 frame adapted to be secured in a rectangular floor opening and having front and rear flanges for support upon the floor, a pair of opposed studs carried by the frame, a door pivotally carried by the studs, and arranged, when closed, to overlap the front part of the frame, and a chute associated with the 85 frame.

5. A waste chute comprising a rectangular 90 frame adapted to be secured in a rectangular floor opening and having front and rear flanges for support upon the floor, a pair of opposed studs carried by the frame, a door pivotally carried by the studs, and arranged, when closed, to overlap the front part of the frame, and a chute associated with the 95 frame, said door having lateral flanges for releasable engagement with said studs.

6. A waste chute comprising a rectangular 100 frame adapted to be secured in a rectangular floor opening and having front and rear flanges for support upon the floor, a pair of opposed studs carried by the frame, a door pivotally carried by the studs, and arranged, 105 when closed, to overlap the front part of the frame, and a chute associated with the frame, said door having a pair of notched extensions adapted to be engaged and disengaged with the studs, when the door is closed, but which cannot be disengaged therefrom when the door is open.

In testimony whereof I affix my signature.

FLOYD O. GRAPP.
